FILLING MACHINE

Robert W. Garrett, Scarsdale, N. Y., assignor to
 Garrett & Company, Inc., Brooklyn, N. Y., a
 corporation of New York

Application June 15, 1949, Serial No. 99,136

8 Claims. (CL 226—96)

1

This invention relates to apparatus for filling bottles and other containers, and has particular reference to a machine for automatically filling respective groups of containers with different fluent materials, such as liquids.

In the marketing of wines, it is common practice to pack bottles of different wines in different cartons and also to pack bottles containing different wines in the same carton. Inasmuch as these practices require filling an excessive number of bottles of the same wine with present day filling equipment before charging the equipment with a different wine, or alternatively, increasing the number of filling machines so that each of several machines fill bottles with a different wine, thus either inordinately increasing the inventory of filled bottles containing a single wine or increasing the number of filling units and consequent space requirements.

In accordance with the present invention, a single filling machine is provided for filling respective groups of containers with different wines, whereby a predetermined number of bottles, say, six, are filled with one kind of wine, another group of six bottles with a different kind of wine, and so on for as many such groups as the machine is supplied with different wines, say four. In this way, and adapting the invention to conventional rotary filling machine practice, the first group of six bottles fed to the rotary carriage will be filled with one wine, say sherry, the second group of six bottles with another wine, say port, the third group of six bottles with a third wine, say sauterne, and so on, all from the same rotary filling machine.

In a preferred embodiment of the invention, the rotating filling machine head, which normally contains the liquid to be filled into the bottles, is provided with segmental different compartments, each containing a different wine which is continuously supplied to that compartment from a separate source, notwithstanding that the head of the machine rotates while performing its bottle-filling function.

More specifically, for a vacuum type of filling machine, the lower portion of the rotating head is subdivided by vertical partitions into four or more compartments, each of which is supplied through a corresponding port in a horizontal partition from an equal number of concentric annular compartments which in turn are respectively supplied with the particular wines or other beverages from stationary filling pipes leading to the corresponding annular compartments. The vacuum is maintained by a stationary suction

5 pipe connected to the interior of the dual tank just described and the remainder of the filling operation is carried on in the conventional way, except that successive groups of predetermined numbers of bottles receive different wines from 10 the corresponding compartments. In applying the invention to a gravity filling type of machine, the wine supply to the annular compartments is made directly through a stationary cover and the filling is carried on in the manner previously described, except by gravity.

15 It will be seen that the present invention affords a very simple but effective way of filling plural groups of bottles with different liquids 20 from the same filling machine, thereby simplifying the operation, eliminating the necessity of maintaining a large inventory of filled bottles pending a change to a different liquid, and also reducing the number of equipment units required 25 for filling different liquids.

For a more complete understanding of the invention, reference may be had to the accompanying drawings, in which:

20 Figure 1 is a vertical section through a vacuum 25 type filling machine embodying the invention, as seen along the line 1—1 of Fig. 2;

Fig. 2 is a transverse section through the filling machine of Fig. 1 as seen along the line 2—2 thereof;

Fig. 3 is another transverse section through the filling machine of Fig. 1 as seen along the line 3—3 thereof; and

Fig. 4 is a vertical section through a modification of the machine of Fig. 1, wherein the filling is performed by gravity.

30 Referring to Fig. 1 of the drawings, numeral 10 designates the stationary base of a conventional form of vacuum type bottle filling machine having a stationary cam track 11 on which roll 35 the cam followers 12 of bottle elevating cylinders 13, guided in suitable sleeves within a rotating carriage 14 and having the bottle supports 15 projecting above the carriage 14 for receiving empty bottles from a conventional bottle feeding mechanism, not shown.

40 Mounted on a hollow standard 16 rotating with the carriage 14 is the head, generally designated 17, from which depend the filling tubes 18 communicating with the interior of the head 17 and carrying the sliding bells 19 and the coil springs 20 against which the bottles B are raised by the bottle supports 15. Either the elevation of the bottles opens a suitable valve 21 or separate means are provided for that purpose to permit 45 the flow of the liquid from the head 17 into each

bottle B in the manner illustrated at the right of Fig. 1. All parts of the machine thus far described are conventional and details thereof form no part of the present invention.

Instead of supplying a single liquid as in conventional machines, head 17 is divided horizontally by a partition 23 into two chambers, one upper chamber 22, and a lower chamber 25, as shown in Fig. 1. The interior of lower chamber 25 is provided with partitions 24 which may be four in number so as to divide it into four segmental compartments 25a, 25b, 25c and 25d, preferably all of the same cubical content as shown particularly in Fig. 3. The partitions 24 extend from the interior wall of the lower chamber 25 to the outer surface of the column 16 which, in the form of machine shown in Fig. 1, also extends upwardly through the upper chamber 22 as shown in Fig. 2.

The upper chamber 22 is subdivided by concentric partitions 26 into annular chambers, equal in number to the segmental compartments 25a-25d within lower chamber 25. Accordingly, since there are four compartments 25a-25d within lower chamber 25, three partitions 26 are employed to divide the upper chamber 22 into four annular compartments 27a, 27b, 27c and 27d, preferably each having the same cubical content, thus requiring the space between the inner partition 26 and column 16 to be wider than its spacing with the next outer partition 26, and so on, until the spacing between the outer partition 26 and the wall of upper chamber 22 is relatively narrow.

Each upper annular chamber compartment 27a-27d communicates with one of the lower segmental compartments 25a-25d through a corresponding opening 28a-28d in the horizontal partition 23, as is shown especially in Fig. 2. Thus, opening 28a in horizontal partition 23 connects outer concentric compartment 27a with lower segmental compartment 25a; opening 28b connects annular compartment 27b with lower compartment 25b; opening 28c connects upper annular compartment 27c with lower chamber 25c, and opening 28d connects upper annular compartment 27d with lower compartment 25d.

Leading upwardly through the hollow column 16 from four separate liquid sources, a, b, c and d, are corresponding stationary pipes 29a, 29b, 29c and 29d. Pipe 29a as it emerges from the upper end of column 16 of the space 30 under the sealed hood 31, turns horizontally and discharges liquid from source a into the outer annular compartment 27a as shown particularly in Fig. 2. Similarly, pipe 29b discharges liquid from source b into annular compartment 27b; pipe 29c discharges liquid from source c into annular compartment 27c, and pipe 29d discharges liquid from source d into annular compartment 27d.

The liquids from the respective sources, a, b, c and d are supplied under sufficient pressure to raise them to the point of discharge into the corresponding annular chambers 27a to 27d by means of suitable pumps, not shown. Accordingly, as the machine discharges the several liquids into successive groups of the bottles B, the supply is continuously replenished from the respective sources a, b, c and d by the corresponding supply pipes 29a to 29d.

The machine shown in Figs. 1 to 3, inclusive, is the so-called vacuum type in which a vacuum is maintained within the liquid supply chamber, in this case, chambers 25 and 22. To that end, a stationary suction tube 32 also extends upwardly

through column 16 into the hood space 30 for creating the vacuum required for operation of this type of machine. It will be understood that the compartments 25 and 22 are air-tight and that hood 31 is sealed air-tightly to the latter.

In operation of the filling machine illustrated in Figs. 1 to 3, inclusive, the empty bottles B are fed by a suitable infeed conveying system to the individual bottle supports 15 of which there may be twenty-four arranged circularly on carriage 14 as indicated especially in Fig. 3. Thus, six bottles are placed immediately beneath each of the compartments 25a to 25d for filling with the liquid contents of the respective compartments 25a to 25d. As the machine rotates, the successive bottles B are raised by cam 11 to insert the corresponding filling tubes 18 into the bottles B and the valves 21 are opened to fill the corresponding bottles B, six bottles will be filled with the liquid contained in compartment 25a, say sherry wine; the next six bottles will be filled with the liquid contained in compartment 25b, say port wine; the next six bottles will be filled from compartment 25c, with say sauterne wine, and the last six will be filled from compartment 25d, say with Burgundy wine. Suitable guiding means in the outfeed conveyors may be employed to divide the groups of bottles containing the different beverages, or they may be hand-segregated, depending upon requirements.

Referring now to Fig. 4, the same arrangement described in connection with the vacuum type of filling machine of Fig. 1 may be here provided for the gravity filling machine, except that the four liquid supply pipes 33a, 33b, 33c and 33d extend through a stationary cover 34 which is sealed over the edge of the rotating head 17' by means of a slip seal 35 which permits the relative rotative movement between the head 17' and the cover 34. The liquid supply pipes 33a to 33d supply respective annular compartments 36a, 36b, 36c and 36d of upper compartment 22' with different liquids and these annular compartments communicate with corresponding segmental compartments in the lower portion of chamber 25' in the same manner as was described in connection with Figs. 1 and 2. The arrangement of the filling tubes 18' and their corresponding valves 21' of Fig. 4 are the same as shown in Fig. 3, the only difference being that the filling operation in Fig. 4 is effected by gravity in a conventional way.

Although the apparatus of this invention is particularly adapted to the filling of different liquids into containers, it is understood that the invention is equally adaptable to filling containers with other fluent materials in the same way. Also, although certain preferred embodiments of the invention have been illustrated and described herein, it is to be understood that the invention is not limited thereby, but is susceptible of changes in form and detail within the scope of the appended claims.

I claim:

1. In a container filling machine, the combination of a revolving container carriage, a revolving filling head positioned above said container carriage, means forming a chamber in said head, partitions dividing said chamber-forming means into a plurality of filling compartments, container filling means leading from each of said compartments for filling an equal number of corresponding containers on said carriage, and separate sources of supply of different fluent filling materials leading severally to the respective compartments in said head.

2. In a container filling machine having a revolving filling head positioned above a revolving container carriage, the combination of a means forming a chamber in said head, partitions dividing said chamber-forming means into a plurality of filling compartments, container filling means leading from each of said compartments for filling corresponding containers on said carriage, a separate supply compartment on said head for each filling compartment and communicating severally therewith, and separate sources of supply of different fluent filling materials leading severally to the respective supply compartments in said head.

3. In a container filling machine having a revolving filling head positioned above a revolving container carriage, the combination of a means forming a chamber in said head, partitions dividing said chamber-forming means into a plurality of filling compartments, container filling means leading from each of said compartments for filling corresponding containers on said carriage, second chamber-forming means on said head above said first chamber-forming means, partitions dividing said second chamber-forming means into a plurality of supply compartments corresponding in number to said filling compartments, means severally connecting corresponding supply and filling compartments, and separate sources of supply of the filling material leading to the several supply compartments in said head.

4. In a container filling machine having a revolving filling head positioned above a revolving container carriage, the combination of a means forming a chamber in said head, radial partitions dividing said chamber-forming means into a plurality of segmental filling compartments, container filling means leading from each of said compartments for filling corresponding containers on said carriage, second chamber-forming means on said head above said first chamber-forming means, partitions dividing said second chamber-forming means into a plurality of annular supply compartments corresponding in number to said filling compartments, means severally connecting corresponding supply and filling compartments, and separate sources of supply of the filling material leading to the several supply compartments in said head.

5. In a container filling machine having a revolving filling head positioned above a revolving container carriage, the combination of a means forming a chamber in said head, partitions dividing said chamber-forming means into a plurality of filling compartments, container filling means leading from each of said compartments for filling corresponding containers on said carriage, second chamber-forming means on said head above said first chamber-forming means, concentric partitions dividing said second chamber-forming means into a plurality of annular supply compartments corresponding in number to said filling compartments, means severally connecting corresponding supply and filling compartments, separate sources of supply of the filling material, a stationary conduit connected to each said source and leading to a corresponding annular supply compartment in said head.

6. In a container filling machine having a revolving filling head positioned above a revolving container carriage, the combination of a means forming a chamber in said head, parti-

tions dividing said chamber-forming means into a plurality of filling compartments, container filling means leading from each of said compartments for filling corresponding containers on said carriage, second chamber-forming means on said head above said first chamber-forming means, concentric partitions dividing said second chamber-forming means into a plurality of annular supply compartments corresponding in number to said filling compartments, means severally connecting corresponding supply and filling compartments, separate sources of supply of the filling material, a stationary conduit connecting each said source and leading to a corresponding annular compartment in said head, and a central tube rotating with said carriage and head and through which said conduits extend upwardly.

7. In a container filling machine having a revolving filling head positioned above a revolving container carriage, the combination of a means forming a chamber in said head, partitions dividing said chamber-forming means into a plurality of filling compartments, container filling means leading from each of said compartments for filling corresponding containers on said carriage, second chamber-forming means on said head above said first chamber-forming means, concentric partitions dividing said second chamber-forming means into a plurality of annular supply compartments corresponding in number to said filling compartments, means severally connecting corresponding supply and filling compartments, separate sources of supply of the filling material, a stationary conduit connecting each said source and leading to a corresponding annular compartment in said head, and a stationary cover for said rotating second chamber-forming means and through which said conduits extend downwardly.

8. In a container filling machine having a revolving filling head positioned above a revolving container carriage, the combination of a means forming a chamber in said head, partitions dividing said chamber-forming means into a plurality of filling compartments, container filling means leading from each of said compartments for filling corresponding containers on said carriage, second chamber-forming means on said head above said first chamber-forming means, concentric partitions dividing said second chamber-forming means into a plurality of annular supply compartments corresponding in number to said filling compartments, means severally connecting corresponding supply and filling compartments, separate sources of supply of the filling material, a stationary conduit connecting each said source and leading to a corresponding annular compartment in said head, a stationary cover for said rotating second chamber-forming means and through which said conduits extend downwardly, and means sealing the joint between said cover and said rotating chamber-forming means.
